UNITED STATES PATENT OFFICE.

ADEN H. ROBERTS AND GEORGE W. WEED, OF WAVERLY, NEW YORK.

BOTTLE CAPPING AND CORKING TOOL.

1,351,539.

Specification of Letters Patent. Patented Aug. 31, 1920.

Application filed May 20, 1920. Serial No. 382,851.

To all whom it may concern:

Be it known that we, ADEN H. ROBERTS and GEORGE W. WEED, citizens of the United States, residing at Waverly, in the county of 5 Tioga and State of New York, have invented certain new and useful Improvements in Bottle Capping and Corking Tools, of which the following is a specification.

This invention relates to bottle sealing implements, and provides a tool principally intended for domestic use, and available either 10 to apply bottle caps such as the so called "crown-seals" or to insert corks.

The device includes two arms hinged together and serving to clamp the bottle neck, and a die-carrying arm hinged to said neck-clamping arms. Implements of this general character have heretofore been devised, but 15 the present invention offers improvements over such prior devices, in the manner of hinging the die-carrying arm to the neck-clamping arms and in the form of the die. These improvements, which will be set forth 20 in detail hereafter, facilitate the application of the device to the neck of the bottle, provide for better guiding of the die, and permit the cap to be positioned in and retained by the die prior to application to the bottle.

A practical embodiment of the invention 25 is illustrated in the accompanying drawings in which:

Figure 1 is a side elevation partly broken away showing the device applied to the neck of a bottle, and the die about to carry a cap 30 into contact with the mouth of a bottle held by the clamping arms.

Fig. 2 is a view similar to Fig. 1, showing the position assumed by the parts at the completion of the sealing operation.

Fig. 3 is a section on the line 3—3 of Fig. 2.

Fig. 4 is a perspective view of the die and a portion of the die-carrying arm looking from beneath.

Fig. 5 is a perspective view of the head casting and portions of the neck-clamping arms, the die-carrying arm being removed.

Fig. 6 is a section on the line 6—6 of Fig. 2.

Fig. 7 is an enlarged fragmentary view of the die intended to show the retaining flange at the mouth of the die.

The operative parts are held together by a head casting 11. This is provided with a 45 rectangular socket to receive one of the neck-clamping arms 12, and with two spaced lugs

13 between which the other neck-clamping arm 14 is pivoted by hinge pin 15. The two neck-clamping arms are formed with opposed complementary seats 16 and 17 designed to receive and confine a bottle neck just beneath the usual mouth flange thereof. 60

Projecting upward from the head casting 11 is a flat lug 18 which lies approximately in the plane of the inner side of the arm 12. This lug is formed with a slot 19, which is slightly inclined to the horizontal in the position that the device assumes when clamped on the neck of an upright bottle. The low end of the slot is the one away from 70 the bottle neck. The purpose of inclining the slot is to eliminate side thrust on the die during its action when initially pressing the cap into contact with the bottle mouth, as will be more fully explained hereafter. 75

The die-carrying arm 20 is slotted at one end and straddles the lug 18. A pivot pin 21 passes through the arm 20 and the slot 19 and serves as a hinge connection for the die-carrying arm. The die 22 is attached to the 80 lower face of the arm 20 by screws 23.

The die 23 is of cup form. At its extreme edge it has an inwardly projecting serrated flange 24. Above the serrated flange 24 is a groove 25 and above the groove 25 the die 85 is sharply contracted. This contracted portion 26 is preferably curved as clearly shown in Fig. 7 and merges into a cylindrical portion 27 whose internal dimension is such as to give proper contracting effect on the corrugated skirt of the seal or cap, when the die is forced down to the limit of its motion, (see Fig. 2). In this position the cylindrical portion embraces the skirt of the cap. 90

The serrated flange 24 and groove 25 are 95 for the purpose of retaining the cap prior to its application to the bottle. The caps as furnished have a widely flaring, corrugated skirt which will snap past the serrated flange 24 when the cap is pressed into the 100 mouth of the die. The serrations while not indispensable enable the die to retain caps which vary considerably in over-all diameter. When the die is forced over the mouth of the bottle, its first effect is to press the 105 cork-washer in the cap against the mouth of the bottle. The sealing pressure is thus applied through the flange of the cap. By increasing this pressure sufficiently, the skirt of the cap yields, and the die slides downward with reference to the cap. The portion 26 bends the skirt of the cap inward so 110

that its corrugations engage under the bead at the bottle mouth in the usual manner. At the completion of the operation, the skirt of the cap is embraced by the cylindrical portion 27 of the die as shown clearly in Fig. 2.

The clamp construction adopted assures the positive guiding of the die. In effect the die-carrying arm is hinged directly to the arm 12 so as to move in a single plane with reference to that arm, and, therefore, with reference to the neck-seat 17 formed therein. Slight variations in the dimensions of the bottle neck are allowed for by making the slot in the end of the arm 20 slightly wider than lug 18.

In using the device, a cap is first inserted in the mouth of the die by pressing it into place so that its flange engages behind the serrated flange 24. The die-carrying arm is turned up and back and the neck-clamping arms are applied to the neck of the bottle just below the mouth flange. The die-carrying arm is then swung forward and downward until the cap seats against the bottle mouth. In this position the die-carrying arm 20 will be approximately parallel with the slot 19 and accordingly there will be no side thrust exerted by the engagement of pin 21 with sides of slot 19. Continued downward movement of the arm 21 applies sealing pressure to the cap and ultimately forces the die down over the cap, bending the corrugated skirt inward as already described. In the latter part of the action of the die, the increasing angularity of the arm 20 with the slot 19 produces a slight, and increasing, side thrust, but this has no disturbing effect, because by this time the cap is fully engaged with the mouth of the bottle, and the die has firmly embraced the cap on all sides.

This implement may also be used for the purpose of forcing corks into the mouths of bottles, the manner of using it for this purpose being obvious from the drawings and description above given.

Having thus described our invention what we claim is:

1. In a bottle capping device, the combination of bottle clamping means; a slotted lug carried thereby; an arm; a cap applying die carried by said arm; and a pin carried by said arm and passing through the slot in

said lug, said slot being approximately parallel to the face of said die at the commencement of the sealing action.

55

2. In a bottle capping device, the combination of bottle clamping arms hinged together; a die-carrier arm; a cap applying die fixed on said die-carrier arm; a slotted lug carried by a bottle clamping arm; and a pin carried by said die-carrier arm and passing through the slot in said lug, said slot being approximately parallel to the face of said die at the commencement of the sealing action.

60

3. In a bottle capping device, the combination of two bottle clamping arms hinged together; a die-carrier arm hinged to one of said clamping arms and confined to swing substantially in a single plane with reference thereto; and a cap-applying die mounted on said die-carrier arm.

70

4. In a bottle capping device, the combination of an arm having a seat to confine a bottle neck; a coacting clamping member serving to press the neck of a bottle into said seat; a die-carrier arm hinged to the first named arm and confined to swing substantially in a single plane with reference thereto; and a cap-applying die carried by said carrier arm.

75

5. In a bottle-capping device, the combination of a head member having an upstanding slotted lug; a bottle clamping arm fixed to said head member; a second bottle clamping arm hinged to said member; a lever having a pin passing through the slot in said lug; and a cap applying die carried by said lever.

85

6. In a bottle-capping device, the combination of an arm having a seat to confine a bottle neck, a coacting clamping member serving to press the neck of a bottle into said seat; a die-carrier arm hinged to the first named arm and confined to swing substantially in a single plane with reference thereto; and a cap-applying die provided with a cap-retaining projection in its mouth, mounted in said die-carrier arm.

90

In testimony whereof we have signed our names to this specification.

ADEN H. ROBERTS.
GEORGE W. WEED.
